UNITED STATES PATENT OFFICE.

JOSHUA THOMAS, OF CLEVELAND, OHIO.

JOURNAL-BOX.

SPECIFICATION forming part of Letters Patent No. 279,461, dated June 12, 1883.

Application filed April 6, 1883. (No model.)

To all whom it may concern:

Be it known that I, JOSHUA THOMAS, of Cleveland, in the county of Cuyahoga and State of Ohio, have invented certain new and useful 5 Improvements in Devices for Applying Anti-Friction Rollers to Journal-Boxes; and I do hereby declare the following to be a full, clear, and exact description of the invention, such as will enable others skilled in the art to which 10 it pertains to make and use the same.

My invention relates to improvements in devices for applying anti-friction rollers to journal-boxes, but more especially to applying said rollers to car-axle boxes, although one part of 15 the device may be applied to road-wagons; and it consists in certain features of construction and combination of parts, as will hereinafter be described, and pointed out in the claims.

In the drawings, Figure 1 is an end view of 20 a car-axle box, showing also an end view of a car-axle and anti-friction rollers. Fig. 2 is a top view of the box. Figs. 3 and 4 are sectional views of a car-axle and box, showing also portions of my new device. Fig. 5 shows 25 a part of my device when applied to axle-bearings where the wheel revolves on the axle, as in road-wagons.

A represents a box with an arm extending on either side, each provided with a seat for a 30 spring, as at A'. The holes at a¹ are for attaching braces. The central portion of the box is bored out to receive the axle B, surrounded by the anti-friction rollers a. These rollers are each pivoted at each end, as at a², in rings, as 35 shown at a². These rings hold the rollers in their respective relative positions to each other.

To the sides of the box A are bolted the 40 flanges C, as shown in Figs. 3 and 4. These flanges do not touch the journal, but hold the rollers in position endwise. The box A is kept in position endwise on the journal by collars on each side of it, as shown at D, d, D', and d', Fig. 3. The collars D and D' are attached to 45 the axle, and have their respective collars d and d' attached to them by loose-fitting dowel-pins, as at d². The collars D and D' are grooved on their faces next their respective attached collars, and these grooves are provided with 50 rings of elastic packing, preferably of rubber,

that when compressed will allow the respective collars to come together, but will also continue to form a tight joint, keeping out dust and retaining the oil in the box when the collars are slightly apart, and will also keep the 55 collars d and d' against their respective flanges C and C'. The side grooves may be made in any shape that is desired; but I prefer the semicircular form, as shown at d². The collar D may be attached to the axle in any suitable 60 manner, or may be formed by the hub of the car-wheel. In either case the collar D' is screwed onto the axle just far enough to leave the movable parts free to turn, and at the same time having as little room for end-play of the 65 parts as possible. The joints between the collars d and d' and their respective flanges C and C' should be ground joints. It will be seen that by this adjustment of parts the rollers a 70 are free from all labor endwise.

When it is not desired to have the axle extend through the outside of the box, an arrangement of parts may be had as shown in Fig. 4, where the flange C' is used, entirely closing the end of the box. In this case the collar 75 b is substituted in place of the collar D' in Fig. 3, and is screwed onto the axle, holding the flange C in place on the axle and preventing undue longitudinal movement of the box. The box, rollers, and the flange C' are then 80 placed in position and held together by the bolts c.

In Fig. 5 is shown the application of the collars D, d, D', and d' as applied to axles of ordinary road-wagons. In this kind of vehicles the 85 joints or bearings between the ends of the hub and the collars or shoulders on the axle are usually packed with leather. This packing is soon worn by the accumulation of dust between the parts, and causes much annoyance by the 90 parts rattling, and also by the free discharge of grease at both ends of the hub. By the application of these collars hereinbefore described the inner collars are, by the elasticity of the said rubber packing, kept in close contact with the ends of the hub, thereby excluding the dust, and consequently reducing the wear of parts, and saving also all annoyance from grease and from the rattling of the parts. Owing to the small size of the collars, when ap- 95 100

plied to road-wagons, it may be advisable not to groove them, but to use the rubber, as shown in Fig. 5 at d^4 .

What I claim is—

5 1. A journal axle-box having a suitable bore for receiving an axle, and arms extending from the upper and lower edges of its sides, which terminate in conjoined portions, provided with seats for springs and holes for attaching the box to the other parts of the truck, substantially as shown and described.

10 2. In a solid box provided with anti-friction rollers and provided with the flanges C and C, the combination, with the adjustable collars D, 15 d , D' , and d' , of the respective elastic packing-rings d^2 and d^3 , forming with their respective collars an extension-joint, keeping the inner collars, d and d' , against their respective flanges, and also keeping out the dust and retaining

the oil in the box, substantially as described, 20 and for the purpose specified.

15 3. The combination, with the collars D, d , D' , and d' and their respective dowel-pins d^2 , of the elastic packing-rings d^4 , making an expansion-joint and keeping the collars d and d' 25 against their respective lateral bearing, thereby keeping out the dust from between the parts and preventing the escape of oil and grease, and also preventing the rattling of the parts, substantially as and for the purpose set 30 forth.

In testimony whereof I sign this specification, in the presence of two witnesses, this 28th day of December, 1882.

JOSHUA THOMAS.
